(57) **CLAIM**

The ornamental design for a display screen or portion thereof with autonomous aircraft passenger animated graphical user interface as shown and described.

DESCRIPTION

FIG. 1 is a first image of a display screen or portion thereof with autonomous aircraft passenger animated graphical user interface according to our new design;

FIG. 2 is a second image thereof;

FIG. 3 is a third image thereof;

FIG. 4 is a fourth image thereof; and,

FIG. 5 is a fifth image thereof.

The appearance of the animated graphical user interface transitions between the images shown in FIG. 1 through FIG. 5. The process or period in which one image transitions to another forms no part of the claimed design.

The dot-dashed-line rectangle illustrates the perimeter of a portion of a display screen and forms no part of the claimed design.

The text and portions of the graphical user interface shown in broken line form no part of the claimed design.
